US00D713010S

(12) **United States Design Patent**
Sada et al.

(10) **Patent No.:** US D713,010 S
(45) **Date of Patent:** ** Sep. 9, 2014

(54) **CONDENSATE OVERFLOW DETECTION DEVICE**

(71) Applicants: **Jonathan M. Sada**, Lawrenceville, GA (US); **Keith H. Platt**, Snellville, GA (US)

(72) Inventors: **Jonathan M. Sada**, Lawrenceville, GA (US); **Keith H. Platt**, Snellville, GA (US)

(73) Assignee: **DiversiTech Corporation**, Duluth, GA (US)

(**) Term: **14 Years**

(21) Appl. No.: **29/465,482**

(22) Filed: **Aug. 28, 2013**

(51) LOC (10) Cl. **23-01**

(52) U.S. Cl.

USPC **D23/249**

(57) **CLAIM**

The ornamental design for a condensate overflow detection device, as shown and described.

DESCRIPTION

FIG. 1 is an overhead isometric view of the front, top and side of a condensate overflow detection device showing my design.

FIG. 2 is a top view thereof.

FIG. 3 is a bottom view thereof.

FIG. 4 is a left side view thereof.

FIG. 5 is a front view thereof.

FIG. 6 is a right side view thereof; and,

FIG. 7 is a rear view thereof.

The broken lines shown are for illustrative purposes only and form no part of the claimed design.
